UNITED STATES PATENT OFFICE

170,924

PENDANT OR SIMILAR ARTICLE

Albert C. Jensen, Mountain View, Calif.

Application January 6, 1953, Serial No. 23,038

Term of patent 14 years

(Cl. D45—17)

To all whom it may concern:

Be it known that I, Albert C. Jensen, a citizen of the United States, residing at Mountain View, in the county of Santa Clara and State of California, have invented a new, original, and ornamental Design for a Pendant or Similar Article, of which the following is a specification, reference being had to the accompanying drawing, forming part thereof.

Figure 1 is a front elevational view of a pendant or similar article, showing my new design, and

The dominant features of my design reside in those portions shown in full lines.

I claim:

The ornamental design for a pendant or similar article, as shown and described.

ALBERT C. JENSEN.
